UNITED STATES PATENT OFFICE.

BENJAMIN F. PRICE, OF BLOOMINGTON, ILLINOIS.

FURNACE.

SPECIFICATION forming part of Letters Patent No. 437,452, dated September 30, 1890.

Application filed June 5, 1889. Serial No. 313,249. (No model.)

To all whom it may concern:

Be it known that I, BENJAMIN F. PRICE, a citizen of the United States, residing at Bloomington, in the county of McLean and State of Illinois, have invented a new and useful Improvement in Air-Heating Stoves and Furnaces, of which the following is a full, clear, and exact description.

My invention relates to improvements in air-heating stoves and furnaces in which there is placed a tapering pipe or conduit with a slot opening in the side and secured inside and to the wall of the combustion-chamber; and the objects of my improvements are to retard the direct escape of all the fat tarry soot and gases and concentrate, superheat, and burn them in a gradual way in straight-draft stoves or furnaces; to produce a uniform fire, that the heat may be more gentle, and to produce and obtain greater economy in the use of fuel. I attain these objects by the mechanism illustrated in the accompanying drawings, forming a part of this specification, in which—

25 Figure 1 is a vertical sectional elevation of my improvement attached to air-heating stoves or furnaces. Fig. 2 is a view in perspective of the conduit as it appears after being disconnected.

30 The invention will first be described in connection with the drawings, and then pointed out in the claim.

35 A represents the combustion-chamber supported upon the fire-pot C and having the fuel-door S. The tapering pipe or conduit B, with the oblong opening or slot A' in the side, is secured inside and to the wall of the combustion-chamber A, and in an inclined position above the said fire-pot C. It is secured

40 by the large end to the top of the combustion-chamber A by bolts b b, near the outer edge of said chamber, and it connects with the flue or

chimney, and the small end projects downward in an inclined position to the fire-pot C on the opposite side of the chamber, and it is 45 there secured to the wall of said chamber by bolt b, leaving the slot or opening A' to admit and concentrate all the gaseous fuel in a sheet form, said fuel then increasing in volume as the size of the chamber of the conduit B permits. While the gas is being concentrated and the flame is beating around the outside wall of said conduit, it becomes so hot that the gas takes fire and is consumed by the intense heat from the inlet or chamber at the 55 lower end, the unconsumable gases escaping to the flue through the large end of the chamber, and the ashes fall back in the fire-pot C through the small end of the chamber.

Having thus fully described my invention, I 60 claim as new and desire to secure by Letters Patent—

Combined with and secured inside and to the wall of the combustion-chamber of an air-heating stove or furnace, a tapering pipe or 65 conduit B, with an oblong opening or slot A' in the side, the end of the chamber that connects with the flue or the escape-way being larger than the inlet or chamber at the opposite end, and the conduit being secured by 70 the larger end to the top of the combustion-chamber A, and near the outer edge thereof, by bolts b b or other suitable means, and projecting downward in an inclined direction to the fire-pot C on the opposite side of said combustion-chamber A, and there secured to the wall near the smaller end of said conduit by bolt b or its equivalent, substantially as described.

BENJAMIN F. PRICE.
